UNITED STATES PATENT OFFICE.

JOHN JOSEPH PAPSON, OF DICKSON CITY, PENNSYLVANIA.

SMOKER'S PIPE.

Application filed September 23, 1927. Serial No. 221,553.

This invention relates to improvements in tobacco pipes and has for an object the provision of a pipe of simple construction; which will insure a cool pure smoke that is free from the harmful effects of nicotine; will prevent the passage of saliva and tobacco juices into the mouth of the smoker, and which may be readily taken apart and assembled for the purpose of cleaning.

10 With the above and other objects in view, the invention further includes the following novel features and details of construction, to be hereinafter more fully described, illustrated in the accompanying drawings and 15 pointed out in the appended claim.

In the drawings:

Figure 1 is an elevation of a pipe constructed in accordance with the invention.

Figure 2 is an enlarged sectional view on 20 the line 2—2 of Figure 1.

Figure 3 is an enlarged fragmentary section taken through the stem of the pipe.

Figure 4 is a bottom plan view showing a fragmentary portion of the pipe stem with 25 the chamber closure removed.

Figure 5 is a detail view of the chamber closure.

Referring to the drawings in detail wherein like characters of reference denote corresponding parts, the reference character 10 indicates the bowl of the pipe from which extends a stem 11, while the mouth piece of the pipe is indicated at 12.

The stem and mouth piece are detachably connected by means of a tapered sleeve 13, the opposite ends of this sleeve having a push joint connection with the stem and sleeve and the adjacent ends of which are reduced as shown. Shoulders 14 and 15 are thus provided upon the stem and mouth piece respectively against which the opposite ends of the sleeve abut. A chamber 16 is thus formed within the sleeve between the opposed ends of the stem and mouth piece.

45 The sleeve is provided in its bottom with an opening 17 which is shown as elongated and which is adapted to be closed by a plate or closure 18. This plate or closure is shaped to conform to the shape of the sleeve and has 50 its opposite ends in sliding engagement with guide lugs 19 positioned upon opposite sides of the opening 17. A combined stop and

holding lug 20 is located at one end of the sleeve, so that when the plate is positioned as shown in Figures 1 and 2 it will securely close the opening 17. The end of the plate remote from the stop 20 is provided with a finger piece 21 by means of which it may be conveniently manipulated.

Extending longitudinally through the stem and mouth piece is a tube 22. One end of this tube is in communication with the bowl 10 and the opposite end in communication with the bore of the mouth piece 12, the tube extending through the chamber 16. The bottom portion of the tube within the chamber 16 is provided with an opening 23 and located within the chamber beneath this opening is an absorbent element 24. This element is preferably in the form of sterilized cotton.

When in use, smoke is drawn through the smoke tube 22 and saliva, tobacco juices and the like will pass through the opening 23 onto the absorbent element 24, so that only cool pure smoke will pass through the mouth piece into the mouth of the smoker. By removing the closure 18, the juice or saliva impregnated cotton may be removed and a fresh piece substituted. Further, by separating the mouth piece and sleeve from the stem, the pipe may be readily and thoroughly cleaned and thus kept in proper condition to insure a cool pure smoke.

The invention is susceptible of various changes in its form, proportions and minor details of construction and the right is herein reserved to make such changes as properly fall within the scope of the appended claim.

Having described the invention what is claimed is:

A tobacco pipe including a bowl, a stem extending from the bowl, a mouth piece, a sleeve connecting the stem and mouth piece and holding said stem and mouth piece in spaced relation to provide a chamber, said sleeve having an opening therein and a closure for the opening, a continuous smoke tube extending longitudinally through said chamber and having its opposite ends extending into the stem and mouth piece and having an opening to provide communication with the chamber.

In testimony whereof I affix my signature.

JOHN JOSEPH PAPSON.
